Office action #2 in corresponding parent U.S. Appl. No. 35/501,354, dated Dec. 28, 2017, indicating the claimed design is patentable.

Primary Examiner — Keli L Hill*(74) Attorney, Agent, or Firm* — Pearne & Gordon LLP**CLAIM**

The ornamental design for a wrapping bag, as shown and described.

DESCRIPTION

FIG. 1 is a front elevation view of a wrapping bag, embodying my new design;

FIG. 2 is a rear elevation view thereof;

FIG. 3 is a right side elevation view thereof;

FIG. 4 is a left side elevation view thereof; and,

FIG. 5 is a bottom plan view thereof.

Design: the upper portion of the front side film is folded outside of the bag; thus, the wrapping bag of the design has additional thickness on the upper sides thereof as a result of its folding; design: the wrapping bag is made of transparent plastic.
